HAMMER DRILL ATTACHMENT FOR
ELECTRIC MOTORS

Earl N. Walter, Denver, Colo.

Application September 3, 1940, Serial No. 355,181

4 Claims. (Cl. 125—33)

This invention relates to a hammer drill attachment for electric motors and like power units having a rotary driven element, and has as an object to provide an improved unitary assembly adapted for operative connection with the rotatably-driven element of such a power unit to convert such rotation into reciprocatory action for use in drilling, riveting, and similar hammering operations.

A further object of the invention is to provide an improved hammer attachment susceptible of convenient selective association with conventional rotary power units to facilitate the drilling of holes in masonry and similar emplacements.

A further object of the invention is to provide an improved hammer unit assembly arranged for convenient practical manipulation in power association with a conventional electric motor for the drilling of holes in masonry emplacements and so located as to be otherwise difficult of access.

A further object of the invention is to provide an improved unitary assembly of cooperating elements constituting a hammer drill attachment for electric power units.

A further object of the invention is to provide a hammer attachment for electric motors that is inexpensive of manufacture, light in weight, arranged for convenient operative association with conventional chuck members of electric motors, and which is efficient and durable in use.

My invention consists in the construction, arrangement, and combination of elements herein-after set forth, pointed out in my claims, and illustrated by the accompanying drawing, in which—

Figure 1 is a side elevation, largely in longitudinal section, of my improved attachment as assembled and operatively connected with the chuck element of an electric motor for practical use. Figure 2 is a bottom plan view of the attachment shown in Figure 1 when separated from its association with a power unit. Figure 3 is a cross section of the improvement taken on the indicated line 3—3 of Figure 1. Figure 4 is a fragmentary, detail section taken on the indicated line 4—4 of Figure 1. Figure 5 is a cross section taken on the indicated line 5—5 of Figure 1.

In the construction of the improvement as shown, the numeral 10 designates the principal frame or body member of the improvement, which frame is preferably formed of metal, in any suitable or desired manner, and comprises an elongated tubular portion having a substantially uni-

form cylindrical bore opening through its ends, spaced, parallel, longitudinal webs or ribs 11 extending transversely from one side of the tubular member along approximately one-half of the tubular member length to define a slot or channel, a handle grip 12 adjacent one end of the tubular member and extending radially thereof in closing relation across the slot between the ribs 11, and a cylindrical, hollow boss 13 projecting from a midportion of the tubular member at one end of the ribs 11 and in axially-perpendicular relation with said tubular member.

The frame 10, and elements 11, 12, and 13 integrally associated therewith, constitutes a pistol-like housing and support for the cooperating elements which comprise the power-transmitting portion of the hammer unit. Received and fitted for axial reciprocation within, and extending at one end beyond, that portion of the bore of the frame 10 remote from the handle 12, a plunger 14 is slidably disposed and is held against relative rotation and limited in the amount of its relative reciprocation by means of a threaded stud 15 which removably engages through a wall of the tubular frame member to position its inner end within a relatively short slot or keyway 16 recessed into an adjacent portion of said plunger. The end of the plunger 14 extending outwardly of and beyond the tubular frame member is fixed to, formed integrally with, or otherwise supports as an axial extension a chuck 17 adapted to receive and hold the shank 18 of a tool, such as a drill bit, thereby disposed in axial alignment with the plunger 14. The chuck 17 may be of any specific construction and mechanical arrangement suited to its purpose, and is shown in the drawing as of a type to slidably receive and frictionally hold the taper shank 18, a suitable slot 19 being formed transversely of the chuck to facilitate removal of the tool shank, when desired. As will be apparent, the plunger 14 is normally held within and in limited sliding relation with the tubular member of the frame 10 in a manner to position the chuck 17 in somewhat spaced relation with the adjacent end of said frame member, removal of the plunger 14 and chuck 17 from the frame member being made possible by the removable character of the threaded stud 15.

In end-abutting relation with the end portion of the plunger 14 housed within the tubular member of the frame 10, a cylindrical impact element 20 is closely fitted and slidably disposed for axial reciprocation within the bore of the tubular frame member, and said impact element

is formed with a radial fin 21 which is fixed to or formed integrally with said impact element 20 and extends beyond the outer periphery of said impact element to lie within and for reciprocation between the frame ribs 11. The impact element 20 has a length less than that of the tubular frame member which is unoccupied by the plunger 14, and said impact element is urged into end contact with said plunger by means of an expansive coil spring 22 disposed in the bore of the tubular frame member to bear at one end against the free end of the impact element and at its other end against a threaded plug 23 which is adjustably engaged with threads formed in the handle end of the tubular frame member bore, said plug 23 thus acting to close the handle end of said bore and also serving as means whereby the expansive tension of the spring 22 may be regulated and adjusted. As will be obvious, the expansive force of the spring 22 acts to urge the impact element 20 against the adjacent end of the plunger 14 and thereby maintain said plunger at its limit of extension outwardly of the frame 10 determined by engagement of the stud 15 within the slot or keyway 16, and the fin 21 is so shaped and associated with the element 20 as to position a straight end margin of said fin disposed radially of the impact element 20 within the cylindrical boss 13 ahead of the junction of said boss with the ribs 11 when the plunger 14 is at the limit of its extension outwardly of the frame 10, as is shown in Figure 1.

A fitting 24 is formed as a closure member for and to threadedly or otherwise removably cooperate with the open outer end of the boss 13, and said fitting is formed with an axial bore disposed in perpendicular relation with the bore of the tubular frame member and with a recessed end which cooperates with the interior of the boss 13 to form a cylindrical chamber wherein a double-lobed cam 25 is mounted for rotation in fixed relation with one end of a shaft 26 which is journaled within the bore of the fitting 24 and extends a considerable distance outwardly beyond the outer end of said fitting. The cam 25 is thus disposed for peripheral engagement against the straight, radially-disposed end of the fin 21, so that as said cam is rotated in the proper direction, the lobes of the cam alternately retract the impact element 20 against the pressure of the spring 22 and release said impact element for impact effect on the plunger 14 deriving from the expansive force of said spring. The outer or free end of the shaft 26 is of a size and specific shape suitable for engagement within and operative association with a clamp-type chuck carried by the driven shaft of an electric motor or an equivalent prime mover, such a chuck being conventionally indicated at 27 and being commonly found as an element of portable electric motors manufactured for general utility purposes. Since the hammer attachment constituting the subject matter of the instant invention is susceptible of use with motors of various sizes and specific constructions, it is believed that no showing or description of the specific power unit and associated chuck construction is necessary or desirable to a complete and competent understanding of the invention.

Since many changes, variations, and modifications in the specific form, construction, and arrangement of the elements shown and described may be had without departing from the spirit of my invention, I wish to be understood as being

limited solely by the scope of the appended claims, rather than by any details of the illustrative showing and foregoing description.

I claim as my invention—

5 1. A hammer attachment for operative association with electric motors and equivalent rotary power units, comprising an elongate frame formed with a longitudinal bore opening through both of its ends, a handle on and disposed radially of one end of said frame, a slot communicating with and radially of said bore through the handled portion of said frame, a plunger mounted for limited reciprocation within and extended at one end outwardly beyond the end of said bore remote from said handle, tool-supporting means associated with the outwardly-extending end of said plunger, an impact element freely reciprocable in said bore for impact effect on said plunger, a radial fin on said impact element slidably engaging in said slot, a plug threadedly engaging the end of said bore adjacent said handle, spring means within said bore engaging between said plug and the adjacent end of said impact element to urge the latter into end engagement against said plunger, a rotatable cam carried by said frame for engagement with one end of said fin to retract said impact element against the pressure of said spring means, and means for operatively connecting said cam with the rotatably-driven element of a power unit.

2. A hammer attachment for selective operative association with an electric motor or equivalent rotary power means, said attachment comprising an elongate frame formed with a straight, longitudinal bore opening through its ends, a handle adjacent and radially of one end of said frame, a slot communicating with and radially of said bore through the handled portion of said frame, a plunger mounted for reciprocation in the end of said bore remote from said handle, tool-supporting means carried by said plunger exteriorly of said frame, an impact element freely reciprocable in said bore for impact effect on said plunger, a radial fin on said impact element slidably received in said slot, a shoulder on the end of said fin adjacent said plunger, a plug threadedly engaging within the end of said bore adjacent said handle, expansive spring means in said bore between said plug and impact element to normally urge the latter into end engagement with said plunger, cam means rotatably carried by said frame for engagement against the shoulder of said fin to retract said impact element against the pressure of said spring, and means for operatively connecting said cam with the rotatably-driven element of a power unit.

3. A hammer attachment for selective association with the rotatably-driven element of an electric motor or equivalent power means, said attachment comprising an elongate frame formed with a longitudinal bore opening through its opposite ends and a handle on and disposed radially of one of its ends, a plunger mounted for limited reciprocation within the end portion of said bore remote from said handle, tool-supporting means carried by said plunger exteriorly of said frame, a longitudinal slide bearing communicating radially with said bore rearwardly of said plunger and opening through the handled end of said frame, an impact element formed with a radial fin engaging said slide bearing mounted for free reciprocation in said bore and for impact effect on said plunger, a

plug threadedly engaging within said bore adjacent said handle, an expansive coil spring in said bore between said plug and the adjacent end of said impact element to normally urge the latter into end engagement with said plunger, a shaft rotatably carried adjacent the forward end of said slide bearing in axially-perpendicular relation with said bore and radially thereof in substantial alignment with said handle, means for connecting the outer end of said shaft with a rotatably-driven power unit, and a cam on the inner end of said shaft for engagement with the forward end of said fin, whereby rotation of said cam acts to retract said impact element against the pressure of said spring.

4. In an attachment of the character described having an elongate frame, a bore longitudinally of and opening through the ends of said frame, a pistol-type handle on and radially of one end of said frame, and a tool-supporting plunger mounted for limited reciprocation in the end of said bore remote from said handle, a cylindrical chamber in a midportion of said

frame and disposed with its axis radially of said bore and substantially parallel with said handle, a slide bearing opening longitudinally between said chamber and the handled end of said frame in communication with said bore, an impact element mounted for reciprocation in said bore, a radial fin on said impact element engaging within said slide bearing, a shoulder on the forward end of said fin and normally disposed within said chamber, a plug threadedly closing the handled end of said bore, an expansive coil spring engaging between said plug and the adjacent end of said impact element to normally urge the latter into end engagement with said plunger, a shaft mounted for rotation axially of said chamber, means for connecting the outer end of said shaft with the rotatably-driven element of a power unit, and a cam fixed to the inner end of said shaft within said chamber for bearing engagement against the shoulder of said fin and consequent retraction of said impact element against the pressure of said spring.

EARL N. WALTER.
